(57) **CLAIM**

The ornamental for a storage case, as shown and described.

DESCRIPTION

FIG. 1 is a front view of a storage case showing my new design;

FIG. 2 is a rear view thereof;

FIG. 3 is a plan view thereof;

FIG. 4 is a bottom view thereof;

FIG. 5 is a right side view thereof;

FIG. 6 is a sectional view thereof taken in the direction of line 6-6 of FIG. 1;

FIG. 7 is a sectional view thereof taken in the direction of line 7-7 of FIG. 1;

FIG. 8 is a sectional view thereof taken in the direction of line 8-8 of FIG. 3;

FIG. 9 is a perspective view thereof;

FIG. 10 is an exploded perspective view thereof;

FIG. 11 is a perspective view of a horizontal plate portion of the storage case, as shown separately to better illustrate claimed detail;

FIG. 12 is a perspective view of a side plate thereof;

FIG. 13 is a perspective view of a back plate thereof;

FIG. 14 is an enlarged perspective view of a coupling assembly part thereof;

FIG. 15 is an enlarged sectional view of a coupling assembly part thereof taken in the direction of line 15-15 of FIG. 14;

FIG. 16 is a reference perspective view thereof showing the storage case in use with the partition plate installed;

FIG. 17 is a reference perspective view thereof showing the storage case in use with the partition plate hovering outside; and,

(Continued)

FIG. 18 is another reference perspective view thereof showing the storage case in use.

The evenly broken lines are shown for the purpose of illustrating unclaimed portions of the storage case and form no part of the claimed design. The dot dash lines are shown to indicate projection lines to related design components and form no part of the claimed design.

The present invention is a storage case to store shoes and clothes. The storage case is composed of horizontal plates, side plates, coupling assembly parts and a dual back plate and dividing partition plate. The storage case is designed to be freely assembled, disassembled, and extended both vertically and horizontally.
